UNITED STATES PATENT OFFICE.

HARRY G. WEEKS, OF CHICAGO, ILLINOIS, ASSIGNOR TO NEW ERA MFG. CO., OF CHICAGO, ILLINOIS.

ELECTRIC CIGAR-LIGHTER.

1,114,207.

Specification of Letters Patent.

Patented Oct. 20, 1914.

Application filed August 5, 1912. Serial No. 713,329.

To all whom it may concern:

Be it known that I, HARRY G. WEEKS, a citizen of the United States of America, and resident of Chicago, Cook county, Illinois, have invented a certain new and useful Improvement in Electric Cigar-Lighters, of which the following is a specification.

My invention relates to electric cigar lighters of the kind in which a high resistance, ordinarily known as the heating unit, is inclosed or maintained in such position that the cigar cannot make contact therewith; and in which the ignition or lighting 15 of the cigar is produced by a current of highly heated air, rather than by direct contact with some highly heated substance or part of the cigar lighter.

Generally stated, the object of my invention is to provide a simple and improved and highly efficient electrical cigar lighter of the foregoing general character.

Special objects are to provide a novel construction and arrangement whereby sufficient heat is produced with a heating unit operating at a lower temperature than heretofore, but of a more durable and satisfactory character, and without danger of over-heating and burning out, whereby the life 25 of the most vital part of the cigar lighter is increased; to provide a novel construction and arrangement whereby the heating unit is embodied in a plug which is easily inserted and removed from the cigar lighter, the latter, for this purpose, being provided with a socket having electrical contacts which close the circuit through the heating unit when the plug is screwed into place, said plug holding the heating unit in the 30 form of a free coil or loop which is practically out of contact with all other parts of the lighter except at the ends or terminals thereof, the said plug being provided with a lateral intake for the air, whereby the current of air enters at one terminal of the heating unit and passes through the convolutions of the latter before encountering the end of the cigar; and to provide certain details and features of construction tending to 35 increase the general efficiency and serviceability of an electrical cigar lighter of this particular character.

To the foregoing and other useful ends, my invention consists in matters hereinafter set forth and claimed.

In the accompanying drawings: Figure 1 is a longitudinal section of the head or upper portion of an electric cigar lighter embodying the principles of my invention, showing in diagram the circuit arrangement thereof, and the dead resistance serving to prevent the burning out of the heating unit of the cigar lighter, as will hereinafter more fully appear. Fig. 2 is a section on line 2-2 in Fig. 1. Fig. 3 is a section on line 3-3 in Fig. 1. Fig. 4 is a perspective of the removable plug containing the heating unit shown in the said previous figures.

As thus illustrated, my invention comprises a support A rising from a suitable base (not shown), provided with a hollow head or casing B, which latter may be removably secured to the said support. Within the said head or casing an electrical socket C is provided, suitably secured in place, said socket having an outer screw threaded electrical circuit closing contact c, and the inner central contact c¹, the two contacts being respectively connected with the wires 70 or conductors c² and c³. The said contacts are insulated from each other in any suitable manner.

The plug D is of porcelain or other suitable insulation, and is provided at its rear end with an outer screw threaded metallic sleeve D that screws into the socket sleeve c, whereby electrical connection is closed between these two parts. The said plug is also provided with a central or rear contact d¹, which makes contact with the contact or terminal c¹ of the socket. The interior of said plug is divided into relatively small and large spaces d² and d³ by the longitudinal partition wall d⁴, which latter has 85 a strip of mica insulation d⁵ secured to the under side thereof and extending forward a distance.

The heating element E is a loose coil of wire having one end or terminal secured to 100 the contact d, and having its lower end extending through an opening in the rear end of the plug to make connection with the contact d¹, whereby a closed circuit is provided when the plug is inserted in place. 105 The side of the plug is preferably provided with an opening d⁶, through which the upper terminal of the said coil or heating unit passes in order to make connections with the contact d, and through which the air 110

passes into the plug and through the convolutions of the said coil or heating unit. For this purpose, to produce a draft of air through the coil or heating unit, the head or casing B is provided with an opening b for the admission of air, and with a perforated front plate b¹, which latter provides for the escape of the highly heated air. The said coil or heating unit can be of any suitable material, but is preferably of nichrome, as this material or metal oxidizes quickly and readily, and produces thereby sufficient superficial insulation to permit the coils or convolutions of the heating unit to contact 15 with each other without short-circuiting the current. The said heating unit is preferably of a comparatively large gage wire, such as .012" diam., and the required resistance is obtained by lengthening the said 20 heating unit or coil until it presents sufficient resistance to enable it to develop the required heat. In this way, and by using a heavier wire, the life of the heating unit is greatly increased, and to prevent the same 25 from burning out, which would be practically certain to happen with the ordinary commercial current, the dead resistance F is placed in the base of the cigar lighter, or in some other portion thereof, and connected 30 in the circuit with the said heating unit. Thus, a sufficient amount of the current is converted into heat for a useful purpose, but at the same time, the strain or wear and tear on the heating unit is much less than 35 heretofore, and with the result that the said heating unit does not break down or deteriorate as quickly as would be the case with heating units of more delicate character of the kind heretofore employed for this purpose. As the wire used for the heating unit 40 is of comparatively heavy gage, it does not tend to chill or cool off, as a result of the influx of cold air through the openings d and d¹, and sufficient heat is absorbed by the 45 air to enable it to ignite the cigar, which latter is presented in the slightly concave end or seat formed at the outer end of the head or casing of the lighter.

The plug D is of exceedingly cheap and 50 economical character, and when the heating unit E breaks or becomes worn out, the said plug can be removed or thrown away and a new one inserted in place thereof. The mica sheet or insulation a¹ keeps the coil or heating 55 unit from becoming displaced, and serves to hold it in position near the apertures of the front plate of the latter. It will be understood, of course, that the said plug D will work in any position—that is to say, 60 it does not need to be rotated until the inner parts thereof are in the position shown in Fig. 1, as it can be inserted and rotated until the contacts of the socket and plug close 65 the electrical circuit, and the exact position of the plug in this respect is unimportant.

The metallic contacts and circuit conductors of the structure may be of any suitable, known or approved material, such as brass or copper, and can be formed or secured in place in any desired manner.

With a circuit of the standard character, say, 110 volts, the heating unit may consist of enough wire of said gage to give approximately 25 ohms resistance, and the dead resistance is substantially the same. This, however, may be varied without departing from the spirit of my invention, as by crowding the convolutions closer together. A coil or heating unit of greater resistance may be employed without increasing the size 80 of the lighter, and thereby reducing the amount of dead resistance necessary to protect the heating unit. This method involves some waste of current, of course, but this is far less than the cost and inconvenience of 85 renewing the heating unit as often as was heretofore necessary.

What I claim as my invention is:

1. An electric cigar lighter comprising a screw threaded socket and electrical connection therefor, a plug removably screwed into said socket, a heating unit contained in said plug, and a perforated plate for keeping the cigar out of contact with said heating unit, permitting the heated air to escape from the plug, said plug having an opening for the admission of air.

2. An electric cigar lighter comprising a screw threaded socket and electrical connection therefor, a plug removably screwed into said socket, a heating unit contained in said plug, a perforated plate for keeping the cigar out of contact with said heating unit, permitting the heated air to escape from the plug, the said plug having an opening for the admission of air, said heating unit consisting of a free coil of wire in the form of a loop, one terminal of said coil passing through the rear end of said plug, and the other terminal thereof passing through the 10 said opening, and contacts on said plug for said terminal.

3. An electric cigar lighter comprising a screw threaded socket and electrical connection therefor, a plug removably screwed into said socket, a heating unit contained in said plug, a perforated plate for keeping the cigar out of contact with said heating unit, said heating unit consisting of a free coil of wire in the form of a loop, one terminal of said coil passing through the rear end of said plug, and the other terminal thereof passing through the side of said plug, contacts on said plug for said terminals, and a wall of insulation extending between the two sides of said loop.

4. An electric cigar lighter comprising a screw threaded socket and electrical connection therefor, a plug removably screwed into said socket, a heating unit contained in

- said plug, a perforated plate for keeping the cigar out of contact with said heating unit, said heating unit consisting of a free coil of wire in the form of a loop, one terminal of said coil passing through the rear end of said plug, and the other terminal thereof passing through the side of said plug, contacts on said plug for said terminal, the bend of said loop being disposed close to the back of said plate, and said plug having an opening for the admission of air at one terminal of said heating unit.
5. In a device of the character disclosed, an electrical socket, a plug for said socket, provided with a hollow body having air admission and outlet openings, said plug having an end contact and a threaded contact,
- 10
- 15

and a resistance in circuit with the contacts of said socket, inclosed within the chamber of said body, said circuit passing through 20 the walls of said plug.

6. A device of the character set forth, comprising a socket, a plug therefor, insertible therein, provided with an air inlet disposed in position not to be closed by said 25 socket when the plug is fully inserted, and a heating unit in said plug, said device having an outlet for the heated air.

Signed by me at Chicago, Illinois, this 31st day of July 1912.

HARRY G. WEEKS.
